UNITED STATES PATENT OFFICE.

GRANT HAMMOND, OF NEW HAVEN, CONNECTICUT, ASSIGNOR OF ONE-THIRD TO ALVA C. WASHBURN, OF PITTSFIELD, MASSACHUSETTS, AND ONE-THIRD TO FREDERICK G. CRANE, OF DALTON, MASSACHUSETTS.

BREECH-BOLT STOP.

1,359,366.

Specification of Letters Patent. Patented Nov. 16, 1920.

Application filed December 1, 1917. Serial No. 204,925.

To all whom it may concern:

Be it known that I, GRANT HAMMOND, a citizen of the United States, residing at New Haven, in the county of New Haven 5 and State of Connecticut, have invented a new and Improved Breech-Bolt Stop, of which the following is a specification.

My invention relates to the class of devices employed for determining the amount 0 of movement of a breech-bolt in a firearm, and more especially a firearm of automatic type, and an object of my invention, among others, is to provide a breech-bolt stop that shall be durable in construction and efficient 5 in its operation.

One form of device embodying my invention and in the construction and use of which the objects herein set out, as well as others, may be attained, is illustrated in the accompanying drawings, in which—

Figure 1 is a view in side elevation of the upper rear portion of a firearm embodying my invention.

Fig. 2 is a view in cross section through the same on plane denoted by dotted line 2—2 of Fig. 1.

The invention illustrated and described herein is a modification of an invention comprised in my copending application filed concurrently herewith and serially numbered 204,921, and reference is hereby made to such application for any understanding that may be desired as to the construction and operation of the firearm aside from the parts embodying this invention.

In the accompanying drawings the numeral 5 indicates a frame including the handle, of my improved firearm, 6 a receiver, 7 a barrel secured to the receiver, 8 a trigger guard, 9 a trigger and 10 a hammer, all of which parts may be of any desired construction, the trigger being connected with the hammer controlling mechanism in any desired manner and the firing mechanism being of any desired type, but including a breech-bolt 11 that is mounted for reciprocating movement in a breech-bolt chamber in the receiver, the invention being especially applicable to a firearm in which movement of the breech-bolt is partially caused by the gases of explosion.

A breech-bolt stop 12 is movably secured in a hole in the side of the breech-bolt, in the preferred form of construction this

opening and the stop extending across a 55 firing pin 13, the stop having a groove 14 through which the firing pin extends and a recess 15 to receive a spring 16 by means of which the stop is held in its operative position to control the movements of the 60 breech-bolt. In the preferred form of construction the spring 16 rests against a spring seat 17 movably located in the recess 15, the end of said seat resting against the bottom of the hole in the breech-bolt in 65 which the parts just described are located.

It is essential that the stop shall be prevented from unintentional releasing move- 70

ment, and to this end I provide means that will effectually secure this result. In the 75 construction herein shown for attaining this end, I provide a lock groove 18, preferably on the under side of the stop and preferably of a more or less V-shape, and I also pro-

vide a lip 19 of similar shape on the bottom edge of the ejection opening 20 in the side of the receiver, this lip being located in the locking groove and effectually retaining the breech-bolt stop in place. In order, however, that the stop may be released 80 from the ejection opening to permit removal of the breech-bolt from the receiver, I provide a releasing notch 21 in the lip 19, this notch being preferably of a width not much greater than the diameter of the stop 85

12, so that the latter can be moved inwardly to release the groove and lip 18 and 19, one from the other, only when the stop is in a predetermined position, and preferably I locate this notch about midway between 90 the ends of the ejection opening 20. With the parts thus arranged it will be perceived that the position at which the stop may be released is not a normal position of rest of the breech-bolt in which positions of rest there would be the greatest liability of accidental release of the stop, but the releasing notch is so located that in operation the stop is always rapidly moving past such point, and it will not remain at such point when 100 the parts are in working order.

In accordance with the provisions of the patent statutes, I have described the principles of operation of my invention, together with the device which I now consider to represent the best embodiment thereof; but I desire to have it understood that the device shown is only illustrative 105

and that the invention may be carried out by other means.

I claim—

- 5 1. A firing mechanism for a firearm including a breech-bolt movably mounted in a breech-bolt chamber in the firearm, a breech-bolt stop projecting from the breech-bolt into an opening in the firearm, to limit the backward movement of the breech-bolt, 10 said stop being attached to said breech-bolt and movable independently thereof for disengaging action, said stop and opening having interengaging parts to prevent disengagement of said stop when the breech-bolt is normally at rest, and means to permit release of said interengaging parts when the breech-bolt is in an abnormal position.
- 20 2. A firing mechanism for a firearm including a breech-bolt movably mounted in a breech-bolt chamber in the firearm, a breech-bolt stop projecting from the breech-bolt into an opening in the firearm, to limit the backward movement of the breech-bolt, 25 said stop being attached to said breech-bolt and movable independently thereof for disengaging action, said stop having a groove, a lip upon the edge of said opening to enter said groove to retain the breech-bolt 30 stop from releasing movement when the breech-bolt is in a normal position of rest, and a releasing notch in said lip to permit release of said stop when the breech-bolt is in an abnormal position.
- 35 3. A firing mechanism for a firearm including a breech-bolt movably mounted in a breech-bolt chamber in the firearm, a breech-bolt stop projecting from the breech-bolt into an opening in the firearm, to limit 40 the backward movement of the breech-bolt, said stop being attached to said breech-bolt and movable independently thereof for disengaging action, said stop and opening having interengaging parts to prevent disengagement of said stop when the breech-bolt 45 is in certain positions, and means to permit release of said interengaging parts when the breech-bolt is in substantially one position only.
- 50 4. A firing mechanism for a firearm including a breech-bolt movably mounted in a

breech-bolt chamber in the firearm, a breech-bolt stop projecting from the breech-bolt into an opening in the firearm, to limit the backward movement of the breech-bolt, said 55 stop being attached to said breech-bolt and movable independently thereof for disengaging action, said stop and opening having interengaging parts to prevent disengagement of said stop when the breech-bolt 60 is in certain positions, and means to permit release of said interengaging parts when the breech-bolt is in an intermediate position.

5. A firing mechanism for a firearm including a breech-bolt movably mounted in a 65 breech-bolt chamber in the firearm, a breech-bolt stop projecting from the breech-bolt into an opening in the firearm to limit the rearward movement of the breech-bolt, said stop having a groove, a lip upon the 70 edge of said opening to enter said groove to prevent release of said stop, and means to permit release of said stop when the breech-bolt is in an intermediate position.

6. A firing mechanism for a firearm including a breech-bolt movably mounted in a breech-bolt chamber in the firearm, a breech-bolt stop projecting from the breech-bolt into an opening in the frame to limit the rearward movement of the breech-bolt, 80 said stop having a groove, and a lip upon the edge of said opening to enter said groove, said lip having an unlocking notch to permit releasing movement of said stop when the breech-bolt is in an intermediate 85 position.

7. In combination with the frame of a firearm having an ejection opening in one side thereof, a firing mechanism including a breech-bolt movably mounted in the 9 breech-bolt chamber in said firearm, a breech-bolt stop projecting from the breech-bolt into said ejection opening to limit rearward movement of the breech-bolt therein, said stop and opening having interengaging parts to prevent disengagement of said stop when the breech-bolt is normally at rest, and means to permit release of said interengaging parts when the breech-bolt is in 95 an abnormal position.

GRANT HAMMOND.
